CLAIM

The ornamental design for a charging station, as shown and described.

DESCRIPTION

FIG. 1 is a front side perspective view of a charging station. FIG. 2 is a front side view of the charging station shown in FIG. 1.

FIG. 3 is a back side view of the charging station shown in FIG. 1.

FIG. 4 is a right side view of the charging station shown in FIG. 1.

FIG. 5 is a left side view of the charging station shown in FIG. 1.

FIG. 6 is a top side view of the charging station shown in FIG. 1; and,

FIG. 7 is a bottom side view of the charging station shown in FIG. 1.

The broken lines shown in the figures are for the purpose of illustrating portions of the charging station that form no part of the claimed design.
